UNITED STATES PATENT OFFICE.

EDWIN P. DAVIS, OF BRIDGEPORT, CONNECTICUT.

THREAD-CUTTING TOOL.

1,332,289.

Specification of Letters Patent.

Patented Mar. 2, 1920.

Application filed March 25, 1918. Serial No. 224,660.

To all whom it may concern:

Be it known that I, EDWIN P. DAVIS, a citizen of the United States, residing at Bridgeport, in the county of Fairfield and 5 State of Connecticut, have invented certain new and useful Improvements in Thread-Cutting Tools; and I do hereby declare the following to be a full, clear, and exact description of the invention, such as will enable others skilled in the art to which it 10 pertains to make and use the same.

My invention relates to cutting-tools to be operated by lathes and especially tools for forming threads.

15 It is practically impossible to cut an accurate thread upon a lathe because to do so all lost motion must be eliminated.

It is the object of this invention to approximate such a condition by providing a 20 tool-holder which shall release itself from any tendency of the lathe to draw the cutting-tool into the work, and which will also prevent side-wise deflection of the cutter. It is necessary to avoid the side-wise deflection 25 of the cutter to prevent changing the lead of the thread. In short, the object of the invention is to prevent any deviation of the cutter and thereby maintain equi-distance between succeeding turns of the thread as 30 measured along the axis of the screw.

To this end my invention comprises the parts and combinations recited in the appended claims.

In the drawings, Figure 1 is a view in side 35 elevation; Fig. 2 is a top plan view; Fig. 3 is a top plan view of the cutter-head; Fig. 4 is a view of the head partly in section and partly in elevation; Fig. 5 is a detail view in horizontal section, showing the application 40 of the cutter to the head; Fig. 6 is a sectional view through the widest part of Fig. 1; Figs. 7 and 8 are detail views of the cutter; Fig. 9 is a perspective view of the clamp which secures the cutter to the head.

45 Broadly speaking the tool is divided into two parts; first, the part including a shank and head by which the tool is secured in the lathe, and second, the head which immediately carries the operating tool proper and 50 is itself carried by the first part.

In this specification I have found it convenient to refer to the first part as a tool-holder and to the second part as to a cutter-head, though it is obvious that in certain

sense the whole of the device, excepting the 55 part of the tool which operates on the material is a tool-holder, and though the head which immediately carries the tool need not necessarily carry a cutter.

I make this statement because my invention may be the subject of various modifications, and may, for example, be used with other tools than the specific thread-cutting tool for which I find it peculiarly applicable.

In these drawings 10 represents the shank 65 of a tool-holder adapted to be fitted to a lathe tool post. The head of the tool-holder is recessed so that in effect it is provided with parallel, separated arms 11 at one end which extend from a head 12 carried at one 70 end of the shank 10.

A cutter head 13 has its shank lying within the recess of the tool-holder head or, as it may be stated, between the arms 11 of the tool-holder head. The cutter head fits into 75 the tool-holder head so that it may be prevented from having any lateral movement, an object further secured by a screw 14 which passes through the parts or arms 11 and through a slot 15 formed in one side of 80 the cutter head, thus permitting the adjustment of the cutter head within the arms or jaws of the tool-holder while securing it firmly against sidewise movement or displacement.

85 From the shank of the cutter-head extends at a right angle a projection which is, in effect, a flat spring-arm, the shank and the projecting spring-arm forming a connection between the cutter head and the tool-holder 90 head substantially of an inverted L-shape. This projection 16 is preferably formed as illustrated in section in Fig. 6 and fits a mortise or slot 17 in the head 12 of the tool-holder being secured in the desired position by means of a set-screw 18. The purpose is to have the tool-head or cutter-head 95 fulcrum upon the spring-arm 16 lying in its adjusted position in the slot 17 of the head 12 of the tool-holder.

100 It will be observed that the spring-arm connection has, relatively, a limited horizontal adjustment in the tool-holder head, and that the spring tension effect applies at the junction between the projecting spring-arm 16 and the shank of the cutter head.

It will be observed that the tool-holder head projects above the cutter-head and

that the spring-arm passes into the top of the tool-holder head from the top of the vertical shank of the cutter-head.

It is necessary to regulate the extent of movement of the cutter head, however, and to this end I have provided an adjusting screw or stop-screw 19 which takes into a threaded projection 190 at the bottom of the cutter-head, or, as it may be stated, at the 5 opposite side from the spring-arm 16. The head of this stop-screw 19 lies opposite the face of the head 12 of the tool-holder and in the space between the parallel arms 11. That is to say, when the projecting arm or 10 shoulder and the projecting spring-arm 16 of the cutter-head are slid into place between the arms 11 of the tool-holder head 12 there will be a space between the cutter-head shoulder and the head 12 of the tool-holder. 15 At the bottom of this space lies the stop-screw 19, and its position within the threaded projection 190 governs the distance of yield of the cutter-head and the amount of 20 play of the cutter-head upon the fulcrum point of the spring-arm 16.

By this device I secure a firm working attachment between the cutter-head and the tool-holder, while at the same time permitting through the action of the spring-arm 30 16, the tool-holder to release itself from any tendency of the lathe to draw the cutter into the work, and also preventing sidewise deflection of the cutter.

The cutter-head 13 is provided with a recess 20 along one side thereof, shaped to receive a cutter 21. A screw 22 engages the cutter head and the cutter so that the cutter may be adjusted vertically. A clamp 23 takes over the face of the cutter-head and 35 40 has an angular projection 24 which fits closely into an angular recess 25 formed in the side of the cutter. Through the clamp 23 passes an attaching screw 26. These parts serve to firmly hold the cutter 21 in any 45 adjusted position upon the cutter head 13.

Having fully described my invention what I claim is,—

1. A thread-cutting or similar instrument, comprising a tool-holder and a cutter-head, the tool-holder having a shank adapted to 50 be fitted to a lathe tool-post, the cutter-head having a spring-arm capable of horizontal adjustment in the tool-holder.

2. A thread cutting or similar instrument, comprising a tool-holder and a cutter-head, 55 the tool-holder having a shank adapted to be fitted to a lathe tool-post and the cutter head having a spring-arm with a horizontal part adapted to enter the tool-holder and to be adjusted horizontally substantially 60 throughout its length in the tool-holder.

3. In a thread-cutting tool or a similar instrument, the combination with a tool-holder having a slotted head, of a cutter-head having a right angle spring arm, the 65 horizontal part of the spring arm adapted to be adjustably secured in the slot in the tool-holder head.

4. In a thread-cutting or similar instrument, the combination of a tool-holder and 70 a cutter-head, the cutter-head having a spring-arm having a vertical part extending above the cutter-head, the vertical part having a projecting arm lying above the plane of the cutter-head and adjustably secured in the tool-holder so that the spring effect is at the junction of the vertical part and the projecting arm.

5. In a thread-cutting or similar instrument, the combination of a tool-holder having a recessed head, a cutter-head having a shank adjustably secured in the recess of the tool-holder head, and an arm projecting from the shank of the cutter-head into the recess of the tool-holder, horizontally adjustable therein and forming a spring connection between the tool-holder and the shank of the cutter-head.

In testimony whereof I affix my signature.

EDWIN P. DAVIS.
